Primary Examiner — Cary M Robinson*Assistant Examiner* — Emily Anna Saunders(74) Attorney, Agent, or Firm — Dunlap Bennett & Ludwig, PLLC(57) CLAIM

The ornamental design for a casino arcade game chip, as shown and described.

DESCRIPTION

FIG. 1 is a top front perspective view of a casino arcade game chip, showing my new design, the top rear perspective view being a mirror image thereof;

FIG. 2 is a front elevation view thereof, the rear elevation view being a mirror image thereof;

FIG. 3 is a front elevation view thereof, the rear elevation view being a mirror image thereof; and,

FIG. 4 is a top plan view thereof, the bottom plan view being a mirror image thereof.

The broken lines shown in the drawings depict portions of the casino arcade game chip that form no part of the claimed design.

The two different types of stippling shown indicate contrasting appearance, wherein the lighter stippling represents one appearance and the darker stippling represents a different appearance, and the two different types of stippling contrast with the adjacent non-stippled portions of the claimed design.
